AUTOMATIC ICE MAKER

Theodore W. Rundell, Abington, Pa., assignor to
 Philco Radio and Television Corporation,
 Philadelphia, Pa., a corporation of Delaware

Application February 26, 1944, Serial No. 524,054

9 Claims. (Cl. 62—106)

This invention relates to refrigerators and has especial reference to apparatus for the automatic production of ice masses, more commonly called cubes.

More particularly, the invention is concerned with an improvement in the apparatus for the automatic and sequential freezing of ice masses for domestic consumption, and the storage of the same in readily available form as disclosed in the copending application of T. W. Rundell, Serial No. 515,958 filed December 28, 1943.

The aforesaid application discloses an apparatus in which ice forming molds mounted in a refrigerator are automatically supplied with water to be frozen, and in which thermo-sensitive means is provided for controlling the flow of said water into the mold and for freeing the frozen masses from the mold member after completion of the freezing cycle, and it is in respect to an improvement in this thermo-sensitive means that the present invention has particular reference.

A principal object of the invention is to provide such ice making apparatus with improved thermo-sensitive means.

Another object of the invention is the provision of a bi-metallic thermo-sensitive device which functions in improved manner to control the flow of water into the molds and to free the frozen masses from the mold after completion of the freezing cycle.

It is also an object of the invention to provide a novel mounting for the thermo-sensitive element which functions to the end that a major portion of the potential energy available in said element will be expended to best advantage and under the most favorable conditions in freeing the frozen masses from the mold.

These and other objects and advantages will be more readily understood by consideration of the following description in conjunction with the accompanying drawings, in which:

Figure 1 is a sectional view of a fragmentary portion of a refrigerator embodying the invention; and

Figure 2 is an enlarged sectional view of the ice molding member and certain associated apparatus.

With particular reference to Fig. 1 of the drawings, the reference character 2 designates a portion of a domestic refrigerator of the mechanical type which may include an outer shell 3 and an inner metal shell or liner member 4, the said liner encasing the food storage compartment 5 and being insulated from the outer shell by suitable thermal insulation 6. The reference numeral 9

indicates a machinery compartment located beneath the food storage space 5, which compartment houses a motor compressor unit (not shown). A horizontal floor member 11 divides the machinery compartment from the upper portion of the cabinet, the insulation 6 being continued across said floor. As the particular refrigerant flow circuit employed to effect cooling of the food storage space forms no part of the present invention, the flow passages and the connections thereto have not been illustrated in the drawings.

In the illustrated embodiment, a double thickness partition 12 provides a floor for the food storage compartment, and a gasket 13 is interposed between the partition members and the adjacent wall portions of the inner liner 4. Mounted beneath this partition is a low-temperature evaporator 14 which comprises a horizontal floor 15, vertical side walls 16 and a central vertical wall 17, dividing the space within said evaporator into a pair of compartments to be maintained normally at freezing temperatures. As shown in Fig. 1, the evaporator is provided with an outwardly turned flange portion 18 at the free edge of each of the vertical walls 16, by means of which the evaporator is supported in the cabinet by connections effected at 19 in the general plane of the partition member 9.

As described in the aforesaid pending application, the apparatus comprises a plurality of ice molding members or cups 20 formed in the lower wall of the evaporator 14, to which cups water is fed from a storage tank 21 located within the food storage compartment 5, the level of the water in the cups being determined and maintained by a suitable float valve mechanism represented generally by the cylindrical housing 22. The operating cycle includes filling of the cups 20 to the desired level, freezing of the contents thereof, and consequent forcible elevation in the cups of the ice masses by means of a temperature responsive element. This upward movement automatically conditions the mechanism to permit the inflow of additional water to fill the space left by the raising of the ice block, after which the freezing cycle is reinitiated.

Walls 23 and 23a extend upwardly from the floor of the evaporator running from the forward to the rearward edge of the evaporator in general parallelism with the side walls 16 and closely adjacent to the cups 20. A pair of cover members 24, 24 are slidingly supported in the evaporator sidewall and the partitions 23 and 23a to form closed spaces around the cups 20. To obtain

access to frozen ice masses, the cover members may be drawn forwardly in their supports.

Describing the ice forming and storing apparatus with more particularity, it will appear that water is delivered from the storage tank 21 (maintained at a temperature above freezing) through a downwardly extending pipe 25, and into the aforesaid float chamber 22. From the float chamber a passage 26 delivers the water to a supply header 27, which is arranged centrally beneath the cup portion of the evaporator 14 to supply water to all the cups, by means of upwardly extending connections 28. Each of these connection passages 28 passes upwardly through a vertical arranged hollow conduit 29, the lower end of which passes through the floor 11 and is in open communication with the motor compressor compartment.

The purpose of these conduits is to conduct sufficient heat from the compressor upwardly to the region of the tubing 28, to insure that freezing will not occur in said tubes, that is, below the level of the lower wall of cups 20. In addition, and to further insure delivery of water to cups 20, the supply header 27 is located closely adjacent to the top wall 11 of the machine compartment.

With reference to Fig. 2, the members 20 are each surrounded by a space 30, which is a part of the refrigerant evaporator circuit and provides for rapid freezing of the water delivered to the cups. In order to maintain a more constant temperature in the very center of cups 20, the refrigerant flow passages 30 are preferably arranged so as to constitute a portion of the refrigerant inlet supply header. Although the refrigerant will be, at least to some extent, active in this zone, this arrangement will maintain the passages 30 in a substantially flooded condition, thereby serving to maintain a more constant temperature throughout the operating cycle.

Although any convenient form of evaporator circuit may be employed, there has been illustrated an evaporator of the type having a balanced central feed passage 31 through the bottom wall thereof from which the refrigerant passes upwardly through parallel connections 32 to exhaust headers 33, one of which is illustrated in Fig. 1.

With reference to Fig. 2, it will be seen that the cups 20 are of generally frustro-conical configuration and are provided with a lower cylindrical part 34. Within this cylindrical portion and adjacent its lower edge is securely mounted an internally threaded flanged sleeve member 36 having an inwardly projecting annular lip portion 37 adjacent its upper end. As shown at 38 the upper surface of the flanged portion of the member 36 is secured to adjacent portion 39 of the evaporator, as by means of welding. A centrally bored plug member 40 has threaded engagement with the inside surface of sleeve 36 and the end of the water supply pipe 28 is mounted within said plug and is secured as by means of the weld indicated at 41. Plug 40 has a lower annular extension 42 of reduced size, to which is secured the upper end of conduit 29. A gasket is shown at 43, interposed between the plug 40 and the flange portion of sleeve 36; and a threaded collar 44 serves to maintain the desired gasket pressure.

An upper annular extension 45 of plug 40 terminates in surface 46 slightly spaced from and beneath lip portion 37 of sleeve 36 and forms with the said lip an annular recess 47 in the bot-

tom of cup 20 within which is positioned the thermo-sensitive element 48 to which the present invention is principally directed.

As illustrated in Fig. 2 and in accordance with the invention, the thermo-sensitive element comprises a bi-metal disk 50 having its peripheral edge portion seated within a circumferential inwardly facing groove 51 of an annular rubber grommet 54. The grommet is provided with an inwardly extending angular flange portion 55 adapted to rest upon surface 46 of plug 40 and shaped so as to form a seat for the disk 50 when it is in the illustrated full line position. The grommet is also provided with an outer bead portion 56 which is confined within the recess between the lip portion 37 and the upper surface 46 of plug 40 in a manner providing a space or clearance 57 between the outer surface of the bead and the inner wall of sleeve 36, which space is sealed against entry of water from the cup 20 by having the vertical dimension of said bead portion sufficiently greater than the corresponding depth of recess 47 that the bead is slightly compressed between the lip and the upper portion 46 of plug 40 in a water-tight manner.

Disk 50 is movable with a snap action between the upper and lower positions illustrated in Fig. 2 in dotted and full lines respectively. The disk carries a valve member 60 fixed to the lower surface thereof, which is adapted to cooperate with a valve seat 61 to control the passage of water through the delivery system to the cup. It will be understood that the valve is carried upwardly when the disk moves to the position shown in dotted lines.

The disk has a number of apertures 62 through which water is delivered to the cup, as herein-after described. Flange 55 of grommet 54 may be provided with upstanding projections 63 for registry with apertures 62 when the disk is in its lower position. These projections serve to close the openings 62 when the disk is in said lower position, in order to prevent formation of ice within said apertures. Disk 50 may be prevented from rotating relative to said grommet by suitable means, such as bonding its peripheral edge within groove 51, so that registry of projections 63 with apertures 62 will not be destroyed.

It should be noted that a ring 65, of rubber or the like, surrounds the top of each of the cups 20 and is provided with an annular lip 66 extending somewhat into the cup opening, said lip having a number of slots formed thereabout. This ring is maintained in position by an apertured plate 67, provided with downwardly turned portions 68 adapted to engage the ring as best illustrated in Fig. 2. As shown in Fig. 1, plate 67 is secured to the fixed evaporator structure.

The operation of the device is as follows: Let it be considered that evaporator 14 is operating, and that no water has as yet been delivered to cups 20; in such circumstance the evaporator circuit including the enlarged flow passages 30 will lower the temperature of cups 20 and therefore of disks 50 to some predetermined minimum temperature, for example in the neighborhood of from 0 degrees to 15 degrees Fahrenheit. The existence of this predetermined minimum temperature causes the thermo-sensitive disk to snap to its upper position (shown in dotted lines) thereby opening the valve 60 and the ports 62. Water now flows from the supply tank 21 and is delivered to the cups through pipes 25 and 28, as described, under regulation of the float valve device 22 and as indicated at 39.

The water thus introduced into the cups 20 will be relatively warm as compared to the temperature of the cup and of the disk 50, this by virtue of the heat exchange taking place through the conduit 29, and due also to the fact that the water supply header 27 is located immediately above the machine compartment. When the cup has been substantially filled with water, to the level indicated at 69, the temperature of the bimetal disk 50 will have been raised sufficiently to cause it to snap back to its lower position shown in full lines, thereby seating the valve 60 against its seat 61, and plugging the disk flow ports 62 to prevent formation of ice therein. It will be understood that the characteristics of the disk must be predetermined so as to cause it to snap between its upper and lower positions in response to the differential temperatures existing during the operating cycle. The disk is capable of exerting an upward force sufficient to break the bond existing between the ice block and the mold member, and to raise said block upwardly a distance equal to the complete travel of said disk.

Due to the action of the evaporator portions 30, the liquid contained in cup 20 is then frozen, during which time the disk remains in its lower position. After the freezing operation is completed, the temperature of the cup and of the block of ice therein will be steadily reduced until a predetermined minimum is reached (for example from 0° to 15° F.), at which time the disk snaps to its upward position, freeing the bond between the ice and the mold and forcing the ice block upwardly in the cup. The reference numeral 69a appearing in Fig. 2, indicates a dot and dash representation of the position of the ice block after it has been so elevated. As the ice block is raised, the resilient lip portion 66 is forced backwardly under the influence of the rising block and thereafter returns to the position illustrated, wherein it will act to maintain the ice mass in the raised position, without the support of disk member 50. From this point on the cycle is repeated, with the thermo-sensitive disk snapping to its lower position and the freezing of the water being reinitiated.

As previously set forth, the disk 50, following completion of the freezing cycle, is subjected to a declining temperature which, in accordance with well known principles, tends to condition the disk for the snap movement to the elevated position, this phase entailing the flattening of the disk into a condition approaching dead center relationship between the central and outer or peripheral portions of the disk in which the aforesaid snap action may occur. In accordance with the present invention, this conditioning phase manifests itself initially in a retractive or downward movement of the outer or peripheral portions of the disk, the said outer portions being free for such movement by reason of the presence of the resilient grommet, and the central portion reacting with the ice mass. The immediate effect of this movement is to strip the disk, except at the central portion from the ice mass, and subsequently the disk snaps to the elevated position. As the peripheral edge portions of the disk 50 draw downwardly, the rubber grommet is displaced outwardly into the space 57 and this displacement of the rubber ring stores therein an appreciable amount of energy which is released at the moment the bond between the ice cube and the cup is broken, and which acts to increase the total upward "travel" of the ice block. Since

the major impulse of which the disk is capable is transmitted when the disk has been distorted to the point where snap action would normally occur, the net effect of the aforescribed operation is to insure the application of such impulse to the ice mass in performance of the double function of the disk to free the ice mass from the walls of the mold and to elevate the mass thus freed.

As described in the aforesaid application, the cyclic operation of the mechanism will continue until a cylinder of ice has been found in each cup which projects upwardly a distance determined by the cover members 24, 24.

While a preferred structural embodiment of the invention has been illustrated and described, the invention contemplates such changes and modifications as may fall within the scope of the appended claims.

I claim:

1. In apparatus for forming ice masses, a mold member adapted to receive water to be frozen, means for freezing the water to form an ice mass, and thermo-sensitive means for freeing said mass from the mold member, said thermo-sensitive means including a bi-metallic element movable by snap action between advanced and normally retracted positions with respect to the mold cavity and in said retracted position being in reactive relation to the ice mass and having a portion thereof free for limited movement away from said mass.

2. In apparatus for forming ice masses, a mold member adapted to receive water to be frozen, means for freezing the water to form an ice mass, and a thermo-sensitive element subject to flexure under changing temperatures between advanced and retracted positions with respect to the mold cavity and reactive with the ice mass to free the said mass from the mold member, said element in retracted position having a portion thereof free for limited movement away from said mass.

3. In apparatus for forming ice masses, a mold member adapted to receive water to be frozen, means for freezing the water to form an ice mass, and a bi-metallic disk subject to flexure under changing temperatures between advanced and retracted positions with respect to the mold cavity and operative to free the ice mass from the mold member, said disk in the retracted position having its central portion in reactive relation to said mass and having the peripheral portions thereof free for limited movement away from said mass.

4. In apparatus for forming ice masses, a mold member adapted to receive water to be frozen, means for freezing the water to form an ice mass, and thermo-sensitive means for freeing said mass from the mold member, said means including a bi-metallic disk forming a portion of the surface of the mold cavity and subject to flexure under the effects of changing temperatures between advanced and retracted positions with respect to said cavity, and resilient supporting means for the peripheral edge of the disk, said resilient means forming a water-tight seal between the said edge and the adjoining portions of the mold and affording freedom for limited movement of the said edge portion of the disk away from the cavity.

5. In apparatus for forming ice masses, a mold member adapted to receive water to be frozen, means for freezing the water to form an ice mass, and thermo-sensitive means for freeing said mass from the mold member, said means including a concavo-convex bi-metallic disk forming a portion of the surface of the mold cavity, and a re-

silent fulcrum for the peripheral edge of the disk about which the disc may flex under changing temperatures between retracted and advanced positions with respect to said cavity.

6. In apparatus for forming ice masses, a mold member adapted to receive water to be frozen, means for freezing the water to form an ice mass, and thermo-sensitive means for freeing said mass from the mold member, said means including a resilient member mounted in a recess in the inner face of the wall of the mold cavity, a bi-metallic disk having its peripheral edge resiliently fulcrumed in said member and subject to flexure under changing temperatures and about said fulcrum between retracted and advanced positions in said cavity, said member providing a seat for the body of the disk when the latter is in the retracted position, an aperture in said disk, and a seat on said member arranged to enter said aperture when the disk is seated on the member.

7. In apparatus for forming ice masses, a mold member adapted to receive water to be frozen, means for freezing the water to form an ice mass, and thermo-sensitive means for freeing said mass from the mold member, said means including a resilient member mounted in the wall of the mold, and a bi-metallic disk having its peripheral edge resiliently fulcrumed in said member and having its central portion arranged for reaction with the ice mass, said disk being subject to flexure under changing temperatures and about said fulcrum between retracted and advanced positions with respect to the mold cavity.

8. In apparatus for forming ice masses, a mold member adapted to receive water to be frozen, means for freezing the water to form an ice mass, and thermo-sensitive means for freeing said mass from the mold member, said means including a resilient member mounted in the wall of the mold, a bi-metallic disk having its peripheral edge resiliently fulcrumed in said member and having its central portion arranged for reaction with the ice mass, said disk being subject to flexure under changing temperatures and about said fulcrum between retracted and advanced positions with respect to the mold cavity, and means affording clearance between the said member and the wall of the mold to permit displacement of said member under the compressive action of the disk.

9. In apparatus for forming ice masses, a mold member adapted to receive water to be frozen, means for freezing the water to form an ice mass, thermo-sensitive means for freeing said mass from the mold member, said means including a resilient member mounted in the wall of the mold, a bi-metallic disk having its peripheral edge resiliently fulcrumed in said member and having its central portion arranged for reaction with the ice mass, said disk being subject to flexure under changing temperatures and about said fulcrum between retracted and advanced positions with respect to the mold cavity, means for admitting water to the mold, and means operatively associated with the disk for controlling said admission.

THEODORE W. RUNDELL.
